UNITED STATES PATENT OFFICE

GEORGE WAYNE LYONS, OF HAYDEN, COLORADO

CONTROLLING MEANS FOR AIRPLANES

Application filed December 20, 1928. Serial No. 327,353.

This invention relates to airplanes and particularly to the controlling mechanism therefor.

One of the objects of the present invention is the provision of wings or supporting planes which are each pivoted upon an axis extending at right angles to the machine and means in connection therewith whereby one wing or the other shall be turned automatically on its axis to change the angle of incidence in case the machine tips laterally on one direction or the other to thereby keep the ship on an even keel without necessitating constant control by the pilot.

15 A further object is to provide means whereby the aviator may change the angle of incidence of either of the wings or both of the wings at his pleasure and as necessity may require.

20 A still further object is to provide for tilting the elevator laterally in consonance with the change of angle of the wings and thus assist in righting the ship or in preventing tail spins.

25 Another object is to provide a mechanism whereby the machine may be steered by changing the angle of incidence of one wing tip or the other, thus doing away with the steering rudder and control therefor.

30 Still another object is to provide landing wheels so operatively connected to the wings that when the landing wheels are released by the pilot and shift to a landing position they will, when they touch the ground, automatically cause the wings to take a braking position to thus bring the machine to a stop and in this connection provide means whereby the wheels will move upward to their inoperative or flying position when the machine leaves the ground, a pilot released latch being provided for automatically holding the wheels in this inoperative position.

35 Other objects will appear in the course of the following description.

40 My invention is illustrated in the accompanying drawings, wherein:—

Fig. 1 is a top plan view of the flying machine constructed in accordance with my invention;

45 Figure 2 is a longitudinal sectional view;

Fig. 3 is a fragmentary elevation of one end of one of the wings and the corresponding wing tip;

Fig. 4 is a fragmentary section on the line 3—3 of Figure 2;

Figure 5 is a section on the line 5—5 of Figure 2;

Figure 6 is a diagrammatic elevation of one of the landing wheels and its wing controlling gear, the landing wheels being in its raised position.

Figure 7 is a like view to Fig. 6 but showing the position of the parts when the landing gear is swung down to its ground engaging position;

Fig. 8 is a like view to Fig. 7 but showing the landing wheel raised to its supporting position by contact with the ground;

Fig. 9 is a fragmentary section of the latch and stop 44;

Fig. 10 is a perspective view of the latch 48;

Fig. 11 is a perspective view of the elevator.

Referring to these drawings, 10 designates the hull or fuselage of the machine which has preferably the shape of a boat, though I do not wish to be limited to this, so that the machine may alight upon the water and will float under these circumstances, the machine being provided with landing wheels and the usual tail skid, if desired, for landing on the ground. The hull or body 10 carries the propeller 11 and suitable motor operated means will be mounted in the bow of the hull for driving the propeller. The hull, it will be seen, is deeper just rearward of the bow than it is at the stern so that, assuming that the machine has landed in the water, the upper edges of the sides of the body will be parallel to the water line, but the keel 12 will rake upward and rearward.

The rear end of the body is tapered at 13. The body is provided with a cockpit for the pilot and a cockpit for an observer or passenger but it is to be understood that I have not attempted to illustrate the details of construction as these may be modified in many ways without departing from the spirit of the invention.

Mounted upon the body are the two wings 14. Each of these wings is pivoted upon a shaft 15 extending longitudinally of the wing and is supported in suitable bearings. The outer ends of the wings may be supported by the outwardly extending brackets or braces 16. These wings have the usual shape of airplane wings from the entering to the exit edge of the wing and may have suitable camber. These wings are independently rotatable with their shafts.

Extending longitudinally of the machine at the middle thereof is a shaft 17 mounted in suitable bearings supported by suitable brackets. This shaft at its rear end is provided with a section 17^a which extends rearward through the rear end of the fuselage and constitutes the shaft section upon which the elevator 19 is adapted to oscillate or rotate. Mounted upon the shaft 17 and depending therefrom into the pilot's cockpit is a rod 20 which is fastened to the shaft 17 at its upper end and is adapted to have swinging motion like that of a pendulum.

Disposed below the lower end of this depending arm or rod 20 is a transverse cable 21 (see Figure 2) which at its ends is supported as will be later described, and slidably mounted upon the arm 20 is a seat 22 carrying a pulley 23 at its lower end which rests upon and travels on the rod 21 which thus in a sense constitutes a track. As before stated, the seat 22 with its pulley 23 is free to move vertically upon the arm 20. Hence the weight of the pilot will rest upon this transverse cable and when the machine is on an even keel, the weight of the pilot will be distributed equally between the two ends of the transverse cable and when the pendulum rod 20 swings to the right or to the left due to the tipping of the machine a greater weight will come upon one end of the cable than upon the other.

Mounted upon each of the shafts 15 is a depending arm 24 which is angularly bent at its lower end as at 25 and extended rearward. This arm extends rearward more or less parallel to the keel 12 of the body and at its rear end is connected by a brace rod 26 to the upper end of arm 24.

This construction in effect constitutes an approximately rigid triangular member mounted on the shaft 15 and adapted to swing forward or rearward. Means are provided, as will be described hereafter, whereby when this arm 24 swings forward, the wing 14 will be tilted at a greater angle of incidence than when the arm 24 swings rearward. The transverse cable 21 is extended over these rearwardly extending arms 25 and at its ends to the fuselage frame at 21^a and is attached thus it will be seen that when the weight of the pilot is shifted from the middle of the cable 21 toward one side, a greater weight will be exerted against one arm 25

than will be exerted against the other arm so that one arm 25 will be depressed and this depression will cause the arm to swing forward, thus tilting the wing on that side upward. Thus if the machine tilts toward the left, all of the weight of the pilot will be brought on the left hand arm 25, swinging this arm 25 and the arm 24 forward, thus tilting the plane or wing on this side to a greater angle of incidence, causing it to exert more lifting power, and consequently lifting the side of the machine. As the machine rights itself, the weight on the bar 21 will be equalized and the tilted aerofoil or wing will be returned to a position coincident with its fellow.

I have illustrated a like rod 20 and a like seat 22 as being supplied for the observer, the pulley 23 on this rear seat 22 bearing, of course, upon the transverse cable 21 at the rear end of the portion 25. This operates in precisely the same manner. It will be noted that because the arm 20 is rigidly attached to the shaft 17, as the machine tilts and as the wing on that side has its angle increased, the elevator 19 will also be tilted, thus resisting any tendency for the tail to side slip.

As it will be seen from Figure 1, the extremities of the wings 14 are frustrated and the extremities of the wings are provided with the wing tips 27 which overlap the extremities of the wings. The shaft 15 which supports each wing 14 may be tubular and have extended through it a shaft 28 which supports the wing tip 27. Each of these shafts 28 extends through the tubular shaft 15 and carries upon its inner end means whereby the shaft may be oscillated under the control of the pilot. Any suitable means may be used for this purpose and I have simply illustrated each shaft 28 as being provided at its inner end with a crank 29, but it is to be understood that other control means for this wing tip might be used. These wing tips are designed to be used for steering purposes so that by depressing one wing tip, this end of the wing will be retarded and the machine will, therefore, turn in the direction of its retardation.

The arms 24 are loosely mounted upon their respective shafts 15 but rigidly mounted upon each shaft or upon the inner end of the wing is a sector 30 having an outwardly projecting stop 31 which will be engaged by the arm 24 as the arm swings forward, thus transmitting movement of the arm 24 to the sector 30 and thus to the corresponding wing. The sector 30 is normally disposed with its stop 31 disposed adjacent the arm 24. This sector 30 is provided with teeth 32 and disposed below each sector 30 is a wheel 33 provided at one point with a series of gear teeth 34 adapted to mesh with the gear teeth 32.

This disk or wheel is mounted upon a shaft or axis 35 carrying upon it the radially ex-

tending arm 36 which carries the landing wheel 37. There are two landing wheels for the machine, one disposed on each side thereof and operatively connected through the wheel 33 with the corresponding sector 30 and thus with the corresponding wing.

The wheel 33 is formed with a relatively long arcuate slot 38 and to the forward end of the sector is pivoted the link 39. This link 10 embraces the margin of the wheel 33 and carries upon it a pin 40 which passes through the slot 38. The upper end of the slot 38 is formed with an inwardly extending notch 41 in which this pin is adapted to rest in a certain position of the parts and below the notch 41 there is provided a cam 42 mounted upon the fuselage in any suitable manner and acting to lift the pin from the notch 41 as will be later described.

20 The periphery of the wheel 33 is formed with a tooth 43 and coating with this tooth is a loop-like latch 44 pivotally mounted upon the fuselage and having its free end urged inward by a spring 45. This latch is provided with a treadle 46 whereby it may be controlled by the pilot and thrown out of engagement with the wheel 33. The wheel 33 is also provided above and rearward of the tooth 43 with a tooth 47 coating with a loop-like latch 48 which embraces the margin of the wheel and which is capable of being forced out of its latching position by means of a pivoted treadle 49 pivoted at 50. When this treadle is depressed by the pilot, its upper 25 end will kick the latch 48 out of engagement with the tooth 47.

The operation of this portion of the machine is illustrated in Figures 6 to 8. Inasmuch as the operation of both landing wheels 40 is the same, I will describe the operation of only one of these landing wheels. In flying position, the wheel 37 is disposed upward above the keel of the fuselage as shown in Figure 6, that is, in a fully raised position. In this position of the parts, the pin 40 is free to move within the slot 38 without in any way affecting the wheel 33 and without being retarded by the wheel 33 so that the tilting of the wing does not in any way affect the wheel 33. The wheel 33 is held in this position with the landing wheel raised by means of the latch 48. When the pilot is about to land, he depresses the treadle 49 which throws the latch 48 out of engagement with the tooth 47. The weight of the landing wheel, and this applies to both landing wheels, of course, now causes the landing wheel and the arm 36 to swing from a raised position to a fully depressed position. This carries the teeth 34 to the position shown in Figure 7 where they will be in mesh with the teeth 32 on the sector 30. As soon as the landing wheels strike the ground, they will swing rearward to a position intermediate the fully depressed position and the fully raised position and the

wheel 33 will turn in a clockwise direction until the tooth 43 is engaged by the latch 44 which will prevent any further rearward movement of the landing wheel.

70 Preferably the inner end of the latch 44 carries within it a spring 51 which cushions the jar due to the rearward movement of the landing wheel under contact with the ground. The landing wheels are now in their landing position and in the position which they occupy in supporting the machine upon the ground.

75 At this time the pin 40 is disposed in engagement with the notch 41. The counter-clockwise movement of the wheel 33 secured by the rearward movement of the landing wheel from its first position to its final landing position acts to swing the sector 30 in a clock-wise direction, acting to tilt the wing downward at its rear end or in other words 80 increase its angle of incidence. This increase in the angle of incidence, of course, causes the wing to act as a brake which brings the machine to a stop without the necessity of this braking action coming upon the tail skid 85 if a tail skid be used and this operation is secured automatically without the intervention of the pilot except as regards the latch 44.

90 Now when the pilot again takes off, he depresses the treadle 46, releasing the latch 44 and releasing the wheel 33. At this time the pin 40 is disposed within the notch 41 and it will be remembered that the wing has a 95 relatively high angle of incidence. The pilot 100 does not depress the treadle 46 until just as the machine leaves the ground, but as soon as he depresses the treadle 46 and releases the wheel 33, the pressure of the air against the rear portion of the wing 14, which rear portion has a greater width than the forward portion of the wing, will cause the rear portion of the wing to swing upward, or in other words, the wing will turn in a counter-clockwise direction and the rod 39 engaging the 105 notch 41 will force the wheel 33 in a clockwise direction lifting the landing wheel 37 and shifting the wheel 33 to its normal position. Just after the wheel 33 has reached this flying position with the landing wheel 110 raised, the cam 42 will engage the pin 40 and force the pin out of the notch so that thereafter the wing is entirely free from the wing 33 and is adapted to be operated either by the pilot or automatically.

115 In order to permit the pilot to control the wings independently of the automatic control therefor, I provide each of the rearwardly extending members 25 with pedals 120 52. It is obvious, therefore, that by pressing forward and downward with one foot or the other, the corresponding lever 24 may be shifted forward to thus increase the angle of incidence of the particular wing or that the angle of incidence of both wings may be 125 130

raised by shifting forward on both of these 5
pedals 52. Of course, when the pilot releases this pressure upon the pedal, the wind acting against the rear portions of the wings rearward of the pivotal center will tend to turn the wings again toward a horizontal position.

It will be understood that the depression of one end or the other of the transverse cable 10 21 acts to force one arm 24 or the other arm forward and that thus the angle of incidence of the wing corresponding to the depressed arm is increased. In the reverse action, it does not occur that the other wing has its 15 angle of incidence decreased by any operation of the corresponding arm 24, but this angle of incidence is decreased by the pressure of the wind acting against the under face of the rear portion of the wing.

20 It will be seen that with this construction the machine will automatically tend to keep on an even keel. If the pilot wishes to turn to the right or to the left he depresses the rear end of the wing tip 27, that is, changes 25 its angle of incidence and then the machine will turn.

20 In turning, the centrifugal force will swing the rod 20 in an opposite direction to the direction in which the machine is turned causing the wing on the side away from that 30 toward which the pilot is turning to increase its angle of incidence, thus lifting that side of the machine and placing the machine automatically in position for banking. If this 35 bank is too great the action of gravity will counteract the centrifugal force and tend to swing the seat 22 reversely, reducing the angle of incidence. If the bank is too little the centrifugal force as before stated will 40 tend to swing the rods 20 in a direction away from that in which the machine is being turned and this will not only tend to increase the angle of incidence of the wing on that side but will also cause the tail to tilt 45 up laterally and thus resist any side slip of the tail.

50 The proportions of the wing tips 27 to the wing may, of course, be varied to any desired extent but inasmuch as the wing tips 27 are only used for steering, these wing tips may be relatively small.

It will be noted that with this construction the angle of the wings is increased at landing so as to secure a braking action and that 55 this relatively high angle of incidence of the wings is retained at the time the machine is taxiing and until it leaves the ground. Then the wings are left free to be operated by the pilot or by the automatic mechanism which I have described.

While I do not wish to be limited to this, I preferably mount the elevator 19 upon the shaft which supports the elevator in such manner that the elevator may be tilted fore 60 and aft, that is, on an axis at right angles to

the axis formed by the shaft 17 or the extension 17^a of the shaft upon which the elevator is mounted and provide the elevator with the usual horns 53 and the usual controlling cords or other controlling devices running to the control stick of the pilot whereby at the pleasure of the pilot, the elevator may be turned from a position where it is coincident with the longitudinal axis of the machine into a tail depressing or tail elevating position as desired or needed. By this means, additional control is given to the pilot who can assist in preventing any tail spins by angling the elevator 19 when it is partially turned or angled by the oscillation of the shaft 17.

It will be noted that the elevator is cut away at 19^a so as to fit upon the conical rear end of the fuselage. This permits the elevator to be turned into a vertical position after the machine has landed as for instance, upon water and under these circumstances, this elevator may be used as a rudder, it being necessary, of course, under these circumstances to disconnect the elevator from the shaft 17 or disconnect this shaft 17 from the rods 20 which are held in engagement with this shaft by screws passing through the collars 20^a or any other suitable arrangement of this character. Of course, under the same circumstances, it will be necessary to disconnect the controls from the control stick. The controls can be used as rudder lines for the purpose of shifting the elevator as a rudder is shifted.

I do not wish to be limited to any particular means for this purpose as it is obvious that many different devices could be used for controlling the elevator when in a vertical position as a rudder.

While I have illustrated a cable 21 as being disposed over the arms 25 for supporting the roller 23, I do not wish to be limited to this as a bar might be used in place of the cable 21, this bar being connected to the arms 25 and supporting the roller 23 so that as the roller is shifted in one direction or the other more or less weight will be brought on one or the other of the arms. Neither do I wish to be limited to the details of construction as illustrated as these may be varied in many ways without departing from the spirit of the invention as defined by the appended claims.

I claim:—

1. An airplane having a fuselage and oppositely disposed wings, each tiltable about the transverse axis to thereby change their angles of incidence, a pendulous, gravity and centrifugally affected element, levers independently operable operatively connected one to each wing and extending longitudinally along the fuselage, a transverse member connecting said levers, the pendulous element operating over and bearing upon said trans-

verse member and causing the depression of one end or the other thereof as the element swings relative to the fuselage to thereby increase the angle of incidence of one wing or the other.

5 2. An airplane having a fuselage and oppositely disposed wings, each tilttable about a transversely extending axis, arms operatively connected to the wings and each arm when moved forward increasing the angle of incidence of the corresponding wing, a connecting member between said arms, a pendulous rod mounted upon the fuselage, a weighted element carried loosely by said rod and having a wheel bearing against said transverse member whereby as said pendulous element swings relative to the fuselage, weight will be shifted toward one or the other of said arms to thus depress one of the arms and cause a change in the angle of incidence of the corresponding wing.

10 3. An airplane having a fuselage and oppositely disposed wings, each wing being independently tilttable about a transverse axis, a horizontally disposed elevator mounted upon the rear end of the fuselage, a longitudinally extending shaft upon which the elevator is mounted, a rod fast to but depending from said shaft, a weight supporting seat slidably mounted upon the rod but swinging therewith, a wheel carried by the seat, levers operatively connected to the wings, the levers when shifted forward increasing the angle of incidence of the wings, and a member connecting the wings and upon which said wheel bears as and for the purpose stated.

15 4. An airplane having a fuselage and oppositely disposed wings tilttable about a transverse axis to change their angles of incidence, independent longitudinally swinging landing wheels one for each wing mounted upon the fuselage, and means controlled by each landing wheel and connected to the corresponding wing causing a change in the angle of incidence of this wing on contact of the landing wheels with the ground.

20 5. An airplane having a fuselage and oppositely disposed wings tilttable around a transverse axis to change their angles of incidence, landing wheels mounted upon the fuselage for longitudinal swinging movement, pilot releasable means for holding said landing wheels in a raised and inoperative position, said means when released permitting the landing wheels to swing to a depending position beneath the fuselage, and operative connections between the landing wheels and said wings increasing the angle 25 of incidence of said wings when the landing wheels strike the ground and are swung rearward, and pilot releasable means preventing the wheels from swinging rearward beyond a predetermined point and holding them at 30 this point until released.

6. An airplane having a fuselage, a wing mounted for rotation on an axis extending transversely of the fuselage, landing wheels mounted upon the fuselage for rearward swinging movement, a sector mounted upon the wing for swinging movement therewith, pilot releasable means for holding the landing wheels raised and in an inoperative position but when released permitting the landing wheels to swing downward into an operative position, and means operatively engaging the sector and engaged with the landing wheels whereby to cause the sector and wing to tilt to a greater angle of incidence when the landing wheels strike the ground and swing rearward, and pilot releasable means limiting the rearward movement of the landing wheels.

7. An airplane having a fuselage, a wing tiltably mounted upon the fuselage for oscillation on a transverse axis, the rear portion of the wing extending rearward beyond the axis a greater distance than the forward portion of the wing extends forward from the axis, landing wheels swingingly mounted upon the fuselage for rearward movement, pilot releasable means for holding the landing wheels raised and in an inoperative position, but when released permitting the landing wheels to swing downward in a position to meet the ground, means actuated by the rearward movement of the landing wheels when in contact with the ground for tilting the wing to increase its angle of incidence, pilot releasable means limiting the rearward movement of the landing wheels, said means when released permitting the lifting of the landing wheels to an inoperative position by pressure against the under face of the wing at the rear of the axis thereof.

8. An airplane having a fuselage, laterally disposed wings tiltably mounted upon the fuselage for oscillation around an axis extending transversely of the fuselage and disposed nearer to the front edge of the wings than the rear thereof, sectors attached to said wings and having interrupted teeth and having a projecting stop, arms mounted for oscillation at one end around the axis of the wings and having rearward extensions, the stops on the sectors being adapted to engage said arms, gravity and centrifugally actuated means automatically causing the forward movement of one arm or the other as the fuselage is tilted to one side or the other, pilot actuated means for shifting one or the other of the arms forward against said stops to thereby tilt the corresponding wings to increase their angles of incidence, a wheel associated with each sector and having a short series of gear teeth thereon, each wheel having a circumferentially extending slot formed with a notch in its upper end, a link pivoted to the forward end of each sector and having a pin engage-

able in said notch, a cam fixed with relation to the corresponding wheel adapted to throw said pin from the notch as the wheel moves in a counter-clockwise direction, arms extending 5 radially from the axis of the wheels and carrying landing wheels, pilot releasable means for holding the first named wheels with the landing wheels raised in an inoperative position but when released permitting said landing wheels to swing downward and forward 10 in a position where they can strike the ground and be swung rearward, and pilot releasable means for limiting the rearward movement of the landing wheels and cushioning the 15 same, said means when released permitting the wind pressure against the under faces of the rear portions of the wings to cause the lifting of the landing wheels to an inoperative position.

20 9. In an airplane having a fuselage and oppositely disposed wings, the wings being mounted upon the fuselage for tilting movement around an axis transverse to the fuselage whereby to increase or decrease the angle 25 of incidence of the wings, gravity and centrifugally affected means for shifting one or the other of said wings to increase its angle of incidence operating automatically as the fuselage is tilted to one side or the other, 30 means whereby the pilot may controllably shift the wings to increase or decrease their angles of incidence, landing wheels mounted on and for longitudinal movement with relation to the fuselage, pilot releasable means 35 normally holding said landing wheels raised but when released permitting the landing wheels to move forward and downward to a ground engaging position, means limiting the rearward and upward movement of the landing 40 wheels upon contact with the ground and locking the landing wheels in landing position, and means actuated by the rearward movement of the landing wheels acting to automatically tilt the wings to an increased 45 angle of incidence to thereby cause the wings to act as a brake.

In testimony whereof I hereunto affix my signature.

GEORGE WAYNE LYONS.
